COMBINED PORTABLE CONTAINER FOR TOOLS
AND ILLUMINATOR THEREFOR

Chris Edmisson, 414 W. Meyer, Kansas City, Mo.

Filed Mar. 2, 1964, Ser. No. 78,834

Term of patent 14 years

(Cl. D55—1)

FIGURE 1 is a side elevational view of a combined portable container for tools and illuminator therefor, showing my new design;

FIG. 2 is a front elevational view thereof;

FIG. 3 is a top plan view thereof; and

FIG. 4 is a view taken along line 4—4 of FIG. 2 of the combined portable container for tools and illuminator therefor.

The dominant features of my design reside in the portion shown in full lines.

I claim:

The ornamental design for a combined portable container for tools and illuminator therefor, as shown and described.
